UNITED STATES PATENT OFFICE.

HENRY H. TAYLOR, OF BRIDGEPORT, CONNECTICUT.

STOCKING-SUPPORTER.

SPECIFICATION forming part of Letters Patent No. 695,349, dated March 11, 1902.

Application filed August 9, 1901. Serial No. 71,526. (No model.)

To all whom it may concern:

Be it known that I, HENRY H. TAYLOR, a citizen of the United States, residing at Bridgeport, in the county of Fairfield and State of Connecticut, have invented certain new and useful Improvements in Stocking-Supporters; and I do hereby declare the following to be a full, clear, and exact description of the invention, such as will enable others skilled in the art to which it appertains to make and use the same.

My invention has reference to certain improvements in stocking-supporters, and has for its objects to render the device more durable, to obtain the full benefits of the elastic element, to enable a better grade of elastic to be used without increasing the cost of the device, to prevent any distortion of the pad element which lies in front of the abdomen, and to cause the pad always to fit firmly and perfectly over the abdomen, whereby a uniform and constant pressure is always exerted against the latter.

With these ends in view my invention consists in the following details of construction and combination of parts, such as will be hereinafter fully set forth and then specifically be designated by the claims.

Referring to the drawings, Figure 1 is a front elevation illustrating my improvement in such form as will enable the same to be attached to the person of the wearer by means of a belt passed around the waist of the wearer; and Fig. 2, a similar view showing the pad element equipped with an approved form of metal-hook fastener, whereby the device may be suspended from the corset-clasp fastener.

Similar numbers of reference denote like parts in both figures of the drawings.

My invention relates to that class of stocking-supporters which employ a pad of some flexible material, adapted to be attached to the person of the wearer in any suitable and well-known manner, while the stocking-engaging tapes or members are attached to and depend from the bottom of the pad.

Heretofore the pad has been made from some sort of cloth fabric possessing no elasticity whatever, while a portion of the stocking-engaging members or tapes was composed of elastic webbing, the result being that the strain on the stocking-engaged members

would cause the pad to become wrinkled and distorted in the line of strain, and this distortion would in a short time cause the metal-hook portion which engages the corset-clasp fastening at the top of the pad to work loose from the pad and in some instances to exert a sawing action upon the corset-clasp. Moreover, these defects which I have noted above materially prevented the pad from exerting any firm or constant pressure against the abdomen, notwithstanding the fact that one of the objects of these pads was to reduce any undue prominence of the abdomen.

My invention contemplates the transfer of the elastic element directly to the pad itself, while the stocking-engaging tapes or members may be wholly non-elastic, the elastic webbing of the pad in my improvement being so disposed that the resilient action is wholly in the direction of the line of strain on the stocking-engaging members.

1 is my improved pad, made of an integral piece of elastic webbing of comparatively broad area, the elastic strands of which are vertically disposed.

Referring to Fig. 1, 2 3 are broken sections of a band or belt secured to the upper portion of this pad, the latter preferably being bound at this point by any suitable tape *a*, said band or belt adapted to be passed around the waist of the wearer to hold the pad in position, while the stocking-engaging tapes or members 4 5 depend from and are secured to the bottom of the pad, the latter being also preferably bound at this part by a suitable tape *b*.

In case the device is to be attached to an element of the corset-clasp fastening an approved form of hook 6 is secured to the top of the pad, while the latter is preferably stiffened by means of a flat steel 7, secured within the top of the pad beneath the tape *a*, as shown at Fig. 2.

When the device is attached to the person of the wearer by means of a belt around the waist, no stiffening will be required at the top of the pad for the reason that the pad is suspended at the top from the corners, and therefore the strain on the stocking-engaging members will not tend to distort the pad; but when the device is constructed as shown at Fig. 2 some sort of stiffening element is

very desirable, since the pad is only suspended at the center of the top portion and the strain on the stocking-engaging members might pull the unsupported sides of the pad downwardly and distort the same so that it could not fit firmly against the abdomen. Also I prefer in constructing my improvement in both its forms to reinforce the elastic element at the top and bottom by means 10 of suitable tapes, so that the belt-sections and the stocking-engaging members will not be likely to tear loose from the elastic element; but I do not wish to be limited in this respect, since it will be clear that the tapes 15 may be dispensed with, the broad feature of my invention residing in the idea of the integral elastic-pad element.

Having thus described my invention, what I claim as new, and desire to secure by Letters 20 Patent, is—

- 25 1. A garment-supporter comprising an integral pad of comparatively broad elastic material, means secured to the upper portion of the pad for supporting the pad in position on the body of the wearer, and means secured to the lower portion of the pad for supporting hose or other garments, substantially as set forth.
2. A garment-supporter comprising an in-

tegral pad formed of comparatively broad 30 elastic material, a binding piece or strip secured to the upper edge of the pad, and a binding piece or strip secured to the lower edge of the pad, the intermediate portions of said pad being permitted to yield in all directions, means attached to the upper binding-strip for supporting the pad in position on the body of the wearer, and means secured to the lower binding-strip for supporting hose or other garments, substantially as 35 40 described.

3. A garment-supporter comprising an integral pad of comparatively broad elastic material, means for suspending the pad from the person of the wearer at a point about 45 midway of its upper edge, a laterally-extending stiffening bar or piece secured to the upper portion of said pad, and means secured to the lower portion of the pad for supporting hose or other garments, substantially as 50 set forth.

In testimony whereof I affix my signature in presence of two witnesses.

HENRY H. TAYLOR.
